United States Patent Office.

DAVID S. QUIMBY, JR., OF BROOKLYN, NEW YORK, ASSIGNOR TO
DAVID S. QUIMBY, OF SAME PLACE.

Letters Patent No. 90,957, dated June 8, 1869.

FIRE-PLACE HEATER.

The Schedule referred to in these Letters Patent and making part of the same

To all whom it may concern:

Be it known that I, DAVID S. QUIMBY, Jr., of Brooklyn, in the county of Kings, and State of New York, have invented and made a certain new and useful Improvement in Fire-Place Heaters; and I do hereby declare the following to be a full, clear, and exact description of the said invention, reference being had to the accompanying drawing, making part of this specification, wherein—

Figure 1 is a vertical section, and

Figure 2 is a plan of said heater sectionally.

Similar marks of reference denote the same parts.

This invention relates to that class of heaters that are set in a chamber formed by the fire-place, and from which the heated air can be taken to an apartment above, or else allowed to escape into the room itself.

My invention relates to a double top to the fire-chamber, to form a heating-surface, and regulate the escape of the products of combustion; also, in arranging the base so as to introduce evaporating-vessels.

The base of the heater is formed with an ash-pit, *a*, below the top plate *b*, and *c* is the grate.

d is a cylinder rising from the plate *b*. I prefer to have this cylinder *d* of sheet-iron, with suitable doors and mica windows.

At the top of the cylinder *d* is my double top, forming a radiator and draught-regulator.

The dome *e* is made to fit the top of the cylinder *d*, and below this is a second flanged dome, *h*, leaving a flue-space, *i*, that opens at one side of the cylinder *d*, into the descending flue *g*, and in the flange of the dome *h* are openings, 2, 3, 3, 4, 4, 5, 5. (See inverted plan of dome, Figure 3.)

The opening 2 is largest, and is opposite where the products of combustion pass off to the flue *g*, and the holes 3 and 4 are gradually smaller, so that the draught and heated products of combustion are thrown forward, toward the front of the heater, to equalize the action of the fire, instead of the gases rushing off directly to the flue *g*.

This construction prevents the cylinder *d* and flue *g* burning out as rapidly as heretofore, and insures a high heat in the top, *e*, which becomes a radiator, to warm the air that ascends around the heater and

within the case *k*, and may pass by the register or damper *l*, and an air-pipe, to the room above; or when the register is closed, all the heat goes into the room containing this fire-place heater.

I provide a hood, *s*, that extends forward and downward from the surrounding frame *k*, and is provided with a register.

This hood aids in directing the heat from the apparatus up through the register *l* and air-tube *m*; but when that register *l* is closed, and the register *n* open, the heat comes out into the room.

The flue *g* opens, at the lower end, into the cross-flue *n*, and passes by the ascending flue *o*, to the chimney.

The base of the heater is slightly elevated, so that air circulates around the same, and passes up behind the base, between that and the casing *k*, (see fig. 1;) and in the spaces at the sides of the ash-pit, I introduce one or two evaporating-pans, *p*, that are mounted as drawers, and provided with an open-work end-support, so that the pan can be taken out for cleaning or filling.

These evaporating-pans, it will be seen in Figure 4, are located where a current of air passes over them, and they are kept warm. These prevent the air becoming vitiated, as heretofore usual with this kind of heater.

What I claim, and desire to secure by Letters Patent, is—

1. The double dome *e* *h*, forming the top of the cylinder *d*, and also a flue, that regulates the escape of the products of combustion, substantially as set forth.

2. The evaporating-pan, introduced into the air-space at the side of the ash-pan, and below the base, *b*, as and for the purposes specified.

3. The hood *s*, extending from the front of the frame, and provided with the register *n*, in combination with the heater-cylinder *d*, and register *l*, as and for the purposes specified.

In witness whereof, I have hereunto set my signature.

DAVID S. QUIMBY, JR.
